UNITED STATES PATENT OFFICE.

WILLIAM LEWIS EVANS, JR., OF WASHINGTON, INDIANA.

HINGE.

1,412,109.

Specification of Letters Patent. Patented Apr. 11, 1922.

Application filed December 22, 1919. Serial No. 346,456.

To all whom it may concern:

Be it known that I, WILLIAM L. EVANS, Jr., a citizen of the United States, residing at Washington, in the county of Daviess 5 and State of Indiana, have invented a new and useful Hinge, of which the following is a specification.

This invention relates to a hinge of the multiple lever type, designed particularly 10 for use on the doors of water closets, clothes closets, screen partitions, wardrobes, garages, coal chutes, wall bed closets, for exterior and communicating doors, and various other structures such as attic windows, ventilators, etc., for causing the doors or sashes to vanish within the stall frames, rooms, or compartments when opened.

The invention is an improvement on the construction shown, described and claimed 20 in my Patent Number 1,367,954, dated Feb. 8, 1921.

The object of the invention is to provide a hinge for the doors, sashes, or other movable parts of the structures named, which when 25 the door, etc., vanishes within the compartment, is caused to lie along the side of the compartment, thereby economizing space, and enabling the use of a shorter compartment, than if the door, etc., were arranged to swing in on ordinary hinges.

A further object of the invention is to provide a hinge for the doors, sashes, or other movable parts of such structures, which is more easily and conveniently operated than 35 the ordinary door or sash hung to swing inwardly, it being possible by the present invention for the operator to stand near to the entrance and close the door or sash, and not have to step or move out of the way, as 40 the door or sash closes by moving around him.

A further object is to provide a hinge which will prevent the door or sash from sagging, will work noiselessly and with little effort, and will not permit the slamming of the door or sash, and which will cause the door or sash to stay open or remain closed, or partially so, making it unnecessary to provide any means for maintaining 50 the door in any set position.

In the aforesaid patent, I have disclosed a hinge for connecting a movable member, such as a door, to a stationary member, such as a booth or other compartment, said hinge 55 comprising two pairs of arms, each pair being located, respectively, at the top and bot-

tom of the door, the pair at the top being pivoted to the inside face of the door and to the top of the compartment, and the pair at the bottom to the inside face of the door 60 and the bottom of the compartment. The pivots of the arms on the door and on the compartment are spaced apart, with the space between the pivots on the door greater than the space between the pivots on the 65 compartment, the pivots on the door being arranged on opposite sides of the vertical center of the door, but nearer to said center than to the side edges of said door. The pivots on the compartment are located, respectively, on the floor and ceiling of the compartment, on a line substantially at right angles to the entrance to the compartment, and at different distances from said entrance. Moreover, each of the pivots on the 70 door and compartment, are made of separate plates.

In the present construction, I prefer to combine the pivots for each pair of arms in a single plate fastened respectively to 80 the door and compartment, and I have located both pivots on the door at one side of the vertical center of the door, and I have placed the pivots on the compartment preferably at the jamb, instead of at the floor 85 and ceiling, thereby giving a clear space to enter the compartment with no part of the hinge standing in the way to step on or trip the occupant going to or from the compartment. In addition, I have made the arms of 90 different lengths and arranged them in different horizontal planes.

The invention will be best understood from a consideration of the following detailed description, taken in connection with 95 the accompanying drawings forming part of this specification, with the understanding, however, that the invention is not confined to any strict conformity with the showing of the drawings, but may be changed and 100 modified, so long as such changes and modifications mark no material departure from the salient features of the invention as expressed in the appended claims.

In the drawings—

Figure 1 is a front view of a pair of water closet stalls showing the invention applied to the doors thereof, one of which is illustrated in the open position, and the other in the closed position;

Figure 2 is a top plan view showing the same positions of the doors;

105

110

Figure 3 is a horizontal section on an enlarged scale illustrating in full lines the closed positions of the door, and in dotted lines the open position thereof;

5 Figure 4 is a partial elevation looking toward the door jamb, showing the door closed;

Figure 5 is a detail perspective view of a plate or socket member mounted on the door 10 jamb;

Figure 6 is a front view of a ventilated closet showing the hinge applied thereto with the door closed;

15 Figure 7 is a horizontal section of the same showing the door open;

Figure 8 is a horizontal section on an enlarged scale, of a ventilated closet, showing in full lines the door closed and in dotted lines the door open;

20 Figure 9 is a vertical transverse section of the same, also on an enlarged scale, looking toward the door jamb;

Figure 10 is a detail perspective view of the door plate or socket member to which 25 the arms are pivoted;

Figure 11 is a detail perspective view showing the pair of hinge arms of different lengths;

30 Figure 12 is an elevation of a door showing two hinges applied thereto, one at the top and bottom;

Figure 13 is a detail perspective view of the type of socket or floor plate shown in Figure 12;

35 Figure 14 is a detail sectional view showing a different form or socket plate for hinging the arms to the jamb;

Figure 15 is a detail perspective view of the type of socket plate shown in Figure 14;

40 Figure 16 is a horizontal section on an enlarged scale, showing the door closed in full lines and the progressive movements of the door to its open position, the construction shown being that illustrated in Figure 12;

45 Figure 17 is a front elevation of a pair of exterior doors showing the hinges applied to the outside thereof;

Figure 18 is a horizontal section on an 50 enlarged scale of the construction shown in Figure 17, showing the door closed in full lines and open in dotted lines, the door plate and jamb plate being of a special construction;

55 Figure 19 is a side elevation showing a pair of arms mounted in connection with the door and jamb plates, which are of the construction shown in Figure 18;

Figure 20 is a front elevation of the jamb 60 plate shown in Figure 19.

Like reference characters indicate corresponding parts on the several figures of the drawing.

In Figures 1 to 5, inclusive, the improved 65 hinge is shown in connection with a water

closet stall, or similar compartment in which 1, 1, designate the side walls or members of the stall having the usual door 2. It is customary in hanging water closet doors to set them up from the floor and 70 down from the top of the opening, and I have followed this plan in illustrating the application of my invention. Figure 1 shows the two doors, the one at the left being closed and the one at the right open. 75 Figure 2 illustrates the same thing in plan view. In this adaptation of the invention, two hinges are all that are necessary, one at the top and the other at the bottom. As the hinges are duplicates of each other, a description of one will suffice for a full understanding of the other.

Fastened to the part which might be termed the door jamb, designated 3, is a hinge element, jamb plate or socket member 4, preferably of the specific form shown in Figure 5. As distinguished from the construction shown in the aforesaid patent, this jamb plate or socket member is preferably made in one piece, and contains a pair of 90 sockets 5, which extend from the top downwardly partway through the plate, as indicated in dotted lines, Figure 4. In this construction, the jamb plate or socket member is shown as fitting snugly in the corner 95 formed by the jamb and the mullion designated 6, and is retained rigidly against the jamb by the provision of a bolt and nut 7, the bolt being passed through the hole 8 of the jamb plate or socket member, (Figure 100 5). A transverse web 9 connects the two sockets at the bottom, and is provided with holes 10, which are used in fastening the jamb plate to the floor whenever the occasion demands. In other words, the jamb 105 plate 4, shown in Figures 3, 4 and 5, may either be fastened directly to the jamb by the bolt 7, or fastened to the floor by bolts or screws entering the openings 10. In either case, however, the jamb plate or socket 110 member will be located substantially in the position shown in Figure 3; that is to say, it will be close to or against the jamb of the door.

It will be observed that by the arrangement shown in Figure 3, the two sockets 5 are spaced at different distances from the entrance to the stall or compartment, and are located in line with each other at one side of said entrance, but are in the same 120 horizontal plane.

Mounted on the inside face of the door, at the top and bottom, are socket members or door plates 11. Each is made of one piece, and this is the preferred construction. They are each provided with a pair of spaced openings or sockets 12 extending upwardly from the bottom nearly to the top, as indicated in dotted lines, Figure 4. One of the door plates or socket members is 130

shown detached in Figure 10. The socket members are located on the inside of the door and at one side of the vertical center thereof, as shown in Figure 2. Each socket member or door plate is secured to the door by screws or bolts.

13, 13^a, designate the individual members of a pair of hinge arms, one pair at the top and one at the bottom. As shown in Figure 10 11, they have downturned terminals 14 and upturned terminals 15, which should be constructed exactly vertical, so as to fit loosely and turn in the sockets 12 of the door plates and the sockets 5 of the jamb plates. These 15 arms are of different lengths and work in different horizontal planes. It will be observed from Figure 11, that the inner arm 13 (the one nearer the door when in closed position) has a short downturned terminal 14, and a longer upturned terminal 15, while the outer arm 13^a has a downturned terminal 14 longer than the corresponding part of the member 13, and an upturned terminal 15 shorter than the corresponding part of 20 arm 13. This construction of the arms is made necessary in order to prevent the elements from interfering with each other when opening and closing the door. This 25 is an important difference over the construction shown in the aforesaid patent, wherein the arms are shown as of the same length.

In the aforesaid patent, the door plates or socket members are disclosed as arranged at opposite sides of the vertical center of 30 the door, whereas, in the construction shown herein, the socket members are combined in one plate which is disposed at one side of the vertical center of the door. Moreover, in the present invention the space between the 35 sockets or pivots on the door is preferably less than the space between the sockets or pivots, on the door jamb.

With the construction shown the pivots on the stationary member are not located on the 40 floor and ceiling, as in my former application, but they are fastened to the door jamb, respectively above the floor and below the ceiling. In other words, I have removed all the plates and arms from the floor, giving 45 a clear space to enter the stall or compartment, and leaving no part of the hinge in the way to step on or trip the occupant going to and from the stall.

Also, by fastening the hinge to the jamb, 50 the door can be set any height from the floor, or down any distance from the top of the opening. In opening the door, the operator does not have to step out of the way of the door, to pull it open, for when 55 the door is pulled toward the operator, it moves from him at the same time.

The operation is very clearly illustrated in Figure 3 of the drawings, wherein the door is shown in full lines in its closed position and in dotted lines in its open posi-

tion. It will be noted that when the door is closed, the inner arm 13 is substantially parallel with the door and the outer arm 13^a is at an angle thereto. At no period of the movement of the arms do they ever 70 assume a parallel position. In the open position, the greater portion of the door vanishes within the stall, only the end of the door projecting beyond the stall entrance. In actual operation, the door moves 75 inwardly twice the length of the long arm. Hence, the extent to which the door vanishes within the stall can be regulated by increasing or decreasing the length of the arms.

In Figures 6 to 9, inclusive, the invention is shown applied to a closet door having a vent space at the bottom, and I have indicated in Figure 9 by arrows how the air enters the closet for ventilation purposes. 80 Precisely the same constructions of door plates, jamb plates and hinge arms as already described, are used in this adaptation of my invention, the only difference being that the jamb plates are secured to the floor 90 and ceiling, respectively, but close to and against the jamb, as shown in Figures 8 and 9 of the drawings. However, the jamb plates can be set up from the floor, if desired, and the special construction of jamb 95 plates provides for this, as previously described.

The operation of the hinge having already been described, it is deemed unnecessary to say anything further on this subject with 100 respect to Figures 6 to 9 inclusive.

Figures 12 to 16, inclusive, show further modifications of the invention. In Figure 12, I have illustrated the same construction of hinge as previously described, applied to 105 a door, with the pivots on the compartment applied to the floor. Figure 16 illustrates in dotted and full lines, the closed and open positions of the door, as well as an intermediate position, it being noted in this connection that the inner arm 13 is parallel with the door when the latter is closed, and that the two arms at no period of their movement assume an exactly parallel position. In these figures, I have shown the 110 socket members 4^a formed of separate plates substantially like those disclosed in my aforesaid patent, but said members are located close to the jamb and in this respect differ from the disclosure of said patent. In this 115 construction, the hinge arms, 13, 13^a, have different lengths, as shown in Figure 11.

Figures 14 and 15 show a construction of jamb plate, or socket member 4^b, of a somewhat different form from that illustrated 120 in Figure 5, this jamb plate being adapted to be secured directly to the jamb, instead of to the floor and ceiling, as illustrated in Figures 12 and 16.

Figures 17 to 20, inclusive, show another 130

modification of the invention wherein the hinges are placed on the outside of the door, and three hinges are shown. In this construction the door plates 11^a are slightly changed so as to provide for the use of a safety bolt 11^b to fasten the same in place. It is necessary to employ this bolt, when the hinge is installed on the outside of the door, so as to prevent the removal of the hinge from the outside. The jamb plate or socket member 4^c has also been modified to provide for a reversible positioning. The sockets 5^a in the jamb plates are made to extend downwardly from the top and upwardly from the bottom, leaving a web or partition 5^b between the pairs of sockets. By this construction, it is not necessary to make the jamb plates right and left hand, but they may be reversed in position to suit the special conditions of use.

As a protection against the hinge being removed from the door when placed on the outside, it will be noted that the downturned terminals on the arms 13, 13^a, come in front of the screws on the jamb plate. Hence, the screws cannot be removed from the jamb plates until the arms are removed, and this is impossible without first removing the door plates. The importance of the safety bolt 11^c on the door plates will be appreciated.

The construction disclosed provides an ideal arrangement for exterior and communicating doors and for closets, booths and rooms which, on account of the use to which they are put, or other reasons, are made small, and which must be provided with doors to close the same. The vanishing door lends itself to such conditions.

Moreover, the objectionable slamming of the door is entirely done away with by this invention, for the door moves slowly yet noiselessly, and its operation may be effected with the expenditure of little effort.

As disclosed, the hinge may be placed either on the exterior or the interior of the door, but it will be understood that the door when opened is thrown to the opposite side from that on which the hinge is placed.

The construction of the hinge is such that the door can be fitted close to the top and bottom of the opening, leaving clearance only for the door to swing.

A door provided with the hinge of this invention is much to be preferred to a door swinging on ordinary hinges, for it is not affected by the wind and conserves space on the exterior; and, where one compartment is adjacent to another, as for instance, where two separate garages are located side by side, in which position an ordinary hinged door could not be swung around without interfering with the other compartment, the door of the present invention is

peculiarly adapted to fill the desired purpose.

The hinge is particularly adapted for use on doors required by law or otherwise to swing outwardly, for the door not only turns outwardly to comply with such requirements, but also moves inwardly at the same time, thereby sheltering the door from the weather and obviating the necessity of providing a fastening means to prevent the wind from moving it.

For communicating doors, it has the peculiar advantage that while it is being opened from the compartment which it closes, it moves backwardly into that compartment, and does not move into an adjoining compartment, only to such an extent as may be permitted by the length of the hinge arms, and these may be made of any desired length. It may often be desired that the door project an equal distance into each room when in an open position.

Not only is the hinge adapted to the use of exterior doors, communicating doors, telephone booth doors, and many other kinds of doors, but it is useful for windows, whether vertically, horizontally or angularly disposed. It is also adapted to such uses as coal chute doors, attic windows, ventilators, for the hinge permits the close fitting of the door or sash when applied thereto. In some constructions, a single pair of arms would be sufficient, in others two pairs, and in still others three or more pairs. I therefore do not wish to be limited to any number.

By the term "compartment" in the claims, I do not wish to be understood as confining myself to a structure bounded by four walls, for the invention should be applied to a door or other movable part employed to close an opening or passageway, in which the opening would not necessarily be an entrance to a definite compartment.

I claim:

1. The combination with a compartment, of a door for closing an entrance or opening thereof, and means for pivotally connecting said door to said compartment, comprising a pair of arms, means for pivotally connecting said arms to said door, and other means for pivotally connecting said arms to said compartment, said last-mentioned means having the pivots spaced apart and located at different distances from the entrance or opening, and disposed wholly within the compartment at that side of said entrance or opening toward or against which said door swings when open.

2. The combination with a compartment, of a door for closing an entrance or opening thereof, and means for pivotally connecting said door to said compartment, comprising a pair of arms, means for pivotally

connecting said arms to said door, and other means for pivotally connecting said arms to said compartment, said last-mentioned means being located at the jamb of the door 5 wholly within the compartment and having the pivots located at different distances from the entrance or opening.

3. The combination with a stationary member, of a movable member for closing 10 an entrance or opening thereof, and means for pivotally connecting said movable member to said stationary member, comprising a pair of arms of different lengths, means for pivotally connecting said arms to said 15 movable member at one side of the vertical center thereof, and other means for pivotally connecting said arms to said stationary member at that side of said entrance or opening toward or against which said movable member swings when open.

4. The combination with a stationary member, of a movable member for closing 20 an entrance or opening thereof, and means for pivotally connecting said movable member to said stationary member, comprising a pair of arms operating in different horizontal planes, means for pivotally connecting said arms to said movable member at one side of the vertical center thereof, and 25 other means for pivotally connecting said arms to said stationary member at that side of said entrance toward or against which said movable member swings when open.

5. The combination with a stationary member, of a movable member closing an 30 entrance or opening thereof, and means for pivotally connecting said movable member to said stationary member, comprising a pair of arms of different lengths and working 35 in different horizontal planes, means for pivotally connecting said arms to said movable member at spaced points at one side of the vertical center thereof, and other 40 means for pivotally connecting said arms to said stationary member at that side of said entrance or opening toward or against which said movable member swings when open.

6. The combination with a stationary member, of a movable member for closing 45 an entrance or opening thereof, and means for pivotally connecting said movable member to said stationary member, comprising a pair of arms, each having an upturned 50 terminal and a downturned terminal, the corresponding terminals of different arms being of different lengths, said arms working 55 in different horizontal planes, means for pivotally connecting said arms to said movable member at one side of the vertical center thereof, and other means for pivotally connecting 60 said arms to said stationary member at that side of said entrance or opening toward or against which said movable member swings when open.

7. The combination with a compartment, of a door for closing an entrance or opening thereof, and means for pivotally connecting said door to said compartment comprising a pair of arms, means for pivotally connecting 70 said arms to said door, a plate carrying a pair of sockets fastened to the jamb, said sockets being located within the compartment at different distances from the entrance or opening of the compartment, 75 and said plate being disposed at that side of said entrance or opening toward or against which said door swings when open.

8. The combination with a stationary member of a movable member for closing 80 an entrance or opening thereof, and means for pivotally connecting said movable member to said stationary member, comprising a pair of arms, means for pivotally connecting said arms to said movable member, and a jamb plate or socket member for pivotally connecting said arms to said stationary member, said jamb plate having a double pair of sockets arranged in different horizontal planes whereby said plate is made reversible.

9. The combination with a compartment, of a door for closing an entrance or opening thereof, and means for pivotally connecting said door to said compartment, comprising 95 a pair of arms, one longer than the other, means for pivotally connecting said arms to said door with one arm arranged substantially parallel to the door when the door is in closed position, and other means for pivotally connecting said arms to said compartment, said means having the pivots spaced apart and disposed at that side of said entrance or opening toward or against which said door swings when open.

10. The combination with a stationary member, of a movable member for closing an entrance or opening thereof, and means for pivotally connecting said movable member to said stationary member, comprising 100 a pair of arms, means for pivotally connecting said arms to said movable member, and other means for pivotally connecting said arms to said stationary member, said last-mentioned means being located entirely within the compartment and disposed at that side of the compartment toward or against which the movable member swings when open, and having pivots spaced apart at different distances from said entrance or opening, and disposed wholly at one side of said movable member when the latter is in closed position.

In testimony that I claim the foregoing as my own, I have hereto affixed my signature 125 in the presence of two witnesses.
